UNITED STATES PATENT OFFICE.

CHARLES A. HORN, OF WOODHAVEN, NEW YORK, ASSIGNOR OF ONE-FOURTH TO W. EVERITT RUNDLE, OF EAST ORANGE, NEW JERSEY, AND ONE-FOURTH TO HAROLD E. LOMBARD, OF BLOOMFIELD, NEW JERSEY.

STEAM-GENERATOR.

1,376,812.

Specification of Letters Patent.

Patented May 3, 1921.

Application filed October 18, 1918. Serial No. 258,702.

To all whom it may concern:

Be it known that I, CHARLES A. HORN, a citizen of Germany, residing at Woodhaven, in the county of Queens, city and State of New York, have invented certain new and useful Improvements in Steam-Generators, of which the following is a full, clear, and exact description.

This invention relates to steam boilers, and among its chief objects is to provide a steam generator of a compact sectional design suitable for extreme high pressures; to provide a steam generator of a compact sectional design in which each and every tube is directly exposed to the radiant heat of the bed of incandescent fuel on the furnace grate and to the convective heat of the furnace gases; to provide a steam generator of compact sectional design in which the tubes are shaped and arranged to form a secondary combustion chamber between each two adjoining sections; to provide a steam generator of compact sectional design in which the furnace gases rise and escape in straight vertical paths without short-circuiting any of the boiler heating-surface; to provide a steam generator of a compact sectional design in which the gases, after having expanded in the primary combustion chamber, are contracted as they leave the latter and again expand in the secondary combustion chambers; and to provide a steam generator of a compact sectional design in which a balanced feed as well as a balanced circulation can be maintained in each section, and independently of the others. To these and other ends the invention consists in the novel features of construction and combinations of elements hereinafter described.

In the preferred embodiment of the invention each section or unit is symmetrical with respect to the central transverse plane and comprises an upper drum extending longitudinally of the furnace, and a lower drum of smaller diameter arranged directly below and parallel to the upper drum. The two are connected by tubes of special shape so that when several sections are arranged side by side to form a boiler, with the upper drums relatively close together large spaces will be left between the lower drums and the tubes to receive the radiated heat from the

fuel on the grate below. The lower spaces between the tubes of the boiler sections constitute also a plurality of secondary combustion chambers or spaces, with which the twyrs hereinafter described are associated. At each end the drums are connected by straight vertical drums arranged outside of the setting proper, to provide large passages for the flow of water, thereby securing rapid and unimpeded circulation in a direction upwardly through its intermediate or evaporating tubes and downwardly through relatively cool vertical drums. Each upper drum is provided with front and rear outlets for connection with front and rear transverse steam mains when several sections or units are arranged side by side to form a boiler, and each upper drum is also provided at each end with a feed-water intake pipe extending down into the adjacent vertical drum, while each vertical drum is equipped near its lower end with a blow-off nozzle or outlet, the latter being preferably connected to an upright sediment pipe or tube inside the drum and the feed-water intake pipe being extended downwardly into the sediment pipe. Each lower drum is provided at its ends with suitable wash-out openings or nozzles. Between the lower drums of two or more boiler sections or units a series of twyrs are provided, to supply preheated air for seconday combustion.

The embodiment thus briefly outlined is illustrated in the accompanying drawings, in which—

Figure 1 shows a complete installation in longitudinal vertical section.

Fig. 2 is a transverse section.

Fig. 3 is a horizontal section about on line 3—3 of Fig. 2.

Fig. 4 is a longitudinal vertical section of a single boiler-section or unit.

Fig. 5 is a detail cross section of one of the upper drums, illustrating the construction and arrangement of the hand-holes and closures.

Fig. 6 is a detail cross section of two adjacent lower drums, showing the arrangement of the twyrs and the air-preheating pipes.

Fig. 7 is a detail section on a plane indicated by the line 6—6 of Fig. 6.

Fig. 8 is a detail plan view of a portion

of a lower drum, at one end of the same, with the water tubes and the adjacent end drum in horizontal section; showing the air-preheating pipes and the connections 5 therefrom to the secondary-combustion twyvers.

Fig. 9 is a detail cross section through the end of two lower drums, taken just inside of the front wall of the setting.

10 Fig. 10 is a detail section on a plane corresponding to line 10—10 of Fig. 9.

The upper or water and steam drums 15 are provided at their ends and near the top with steam-outlet nozzles 16 to which are 15 welded or otherwise suitably secured the ends of the steam intake dry pipes 17, open at the top to receive steam from the steam space and extending longitudinally inside the drums well above the water level. The 20 nozzles 16 are connected to the transverse steam mains 18, 19, at the front and rear of the boiler, by means of the connecting pipes or connectors 20, 21. The steam mains are made in sections of suitable length to accommodate 25 the desired number of boiler sections and are flanged at their ends for convenient connection with each other when several groups of boiler sections are used together or for connection to the steam line, 30 not shown, leading to the engines or turbines. Each upper drum is also provided with two rows of hand-holes, on opposite sides of the central longitudinal plane of the drum and staggered with respect to each 35 other, each hand-hole serving three tubes. The hand-holes, which are preferably circular in shape, are closed by inner tapered closures 22, Fig. 5, drawn firmly up against their seats 23 by means of nuts 24 on the 40 closure stems 25 which pass through the spiders 26. The stems are also provided with lock nuts 27. The slots 23, on which the spiders and conical closures bear, are in the form of collars suitably secured in the 45 openings in the drum, preferably by welding. The closure devices are covered and protected by removable caps 28, which are centered by inner ribs 29. Each upper drum is also provided at its ends with hand- 50 holes in the form of flanged nozzles 30, Fig. 4, closed by removable covers 31 and located above the respective end drums. At the end of each upper drum, near the bottom thereof, are the feed-water inlet nozzles 32 55 to which are secured the feed-water inlet pipes 33, more fully described hereinafter. The lower drums 34, which, it will be observed, are considerably smaller than the upper drums, are provided at their ends 60 near the bottom with wash-out nozzles 35, having removable closures 36, Fig. 3.

The upright water tubes 37 of each boiler section or unit are arranged in two rows, staggered in plan (see Figs. 3 and 8), the 65 tubes of each row being inclined down-

wardly and inwardly, toward those of the other row until the two rows overlap or intermesh, so to speak, as clearly shown in Fig. 2. Below that point the tubes curve outwardly into connection with the lower drums. This 70 arrangement affords wide spaces for flame and gases rising from the grate and exposes the outer sides of all the tubes to heat radiated from the incandescent fuel. For the purpose of burning in these spaces any combustible gases which may have escaped combustion below, I provide between each two lower or water drums 34 a longitudinally extending series of twyvers 38, Figs. 2, 3, 6, 7 and 8. The twyvers are in the form of refractory bricks extending from drum to drum and having their lower corners cut away to permit the bricks to set down between and upon the drums. The twyver bricks are arranged between the water 85 tubes, in staggered relation, as clearly shown in Figs. 3 and 8. Each brick is grooved on its top and has a correspondingly grooved removable cover 39, providing a longitudinal passage 40 (transverse 90 with respect to the drums) opening into the elongated port 41 in the side of the cover about midway between its ends. As will be seen in Fig. 6, the aforesaid grooves and the air passage 40 formed thereby do not extend the full length of the brick but terminate at the end of the outlet or discharge port. In other words the air passages are closed at one end. The air supplied to the twyver bricks is delivered by nipples 42, 100 Figs. 6 and 8, on the air pre-heating pipes 43, cradled between the lower ends of the water tubes. These nipples extend into the open ends of the air-passages 40, and the pipes themselves (connected to a suitable 105 source of pre-heated air under pressure, not shown) extend into the setting from the front or rear as may be most convenient. The ports 41 discharge directly into the spaces between the groups of water tubes at 110 the bottom thereof, as shown in Fig. 6, which spaces constitute the openings through which the gases pass from the primary to the secondary combustion chambers. The contraction of the gases to enable them to 115 pass through these spaces, followed by their expansion into the secondary combustion chambers, promotes thorough commingling of the gases and hence facilitates combustion of any unburned portions. 120

The vertical end drums 44, Figs. 1 and 4, are suitably protected or more or less insulated from the heat of the furnace, for example by locating them outside of the front and rear walls 45, 46 of the boiler setting. On the other hand, the water tubes are directly exposed to the heat. The circulation in the boiler is therefore upward through the water tubes and downward through the vertical drums. The aforesaid 125 130

walls 45, 46, are preferably composed of refractory tiles and are supported by the lower horizontal drums, the tiles of the lower course 47, Fig. 9, being specially shaped to fit the drums. Between the groups of water tubes the tile separating walls are provided with peep holes 48, Figs. 1 and 2, at which points special tiles 49, having horizontal apertures registering with the peep holes, are arranged between the vertical drums. The relatively thin front and rear outer walls 45^a, 46^a, Fig. 1, are provided to further insulate the vertical drums and prevent loss of heat.

15. The feed-water intake pipes 33, Fig. 4, which may be connected to a common supply pipe, not shown, extend down into the upright sediment pipes 50, Fig. 4, inside of the vertical end drums 44. The sediment pipes are supported in any convenient manner, not shown, and have their lower ends extended into the upturned ends of the blow-off elbows or nozzles 51 near the lower ends of the drums. The provision of means for delivery of feed-water at each end of each section makes a "balanced" circulation in the boiler possible; that is, the feed-water has the same effect upon the circulation in both vertical drums and the same in all the

30 sections.

As shown in Fig. 2, the boiler sections or units (each composed of upper and lower drums and appurtenances as already described) are preferably arranged in groups separated by vertical walls 52, each group thus constituting a boiler. Each boiler section is supported by its upper drums, which rest in U-shaped hangers 53, Fig. 1, suspended from transverse I beams 54 resting on longitudinal I beams 55 suitably mounted on the vertical columns 55^a. The lower drums fit into recesses in the top of the front and rear walls of the combustion or grate chamber, and provision is made for the downward expansion of the water tubes by making these recesses of suitable depth. The spaces thus left under the lower drums may be packed with asbestos, as indicated at 56, Figs. 9 and 10.

50. If a superheater is used, the pipes or coils are preferably located between the boiler sections or units, just below the row of upper drums, as indicated at 57, Fig. 2, or at a lower position if a higher degree of superheat is desired. The superheater, however, is not a part of the present invention and hence is not illustrated herein.

Each boiler, or group of boiler sections has its own combustion chamber and grate, 60 directly below the lower drums. The grates and stoking mechanisms are preferably of the type described in my prior patents Nos. 1,261,389 and 1,271,710, dated April 2, 1918, and July 9, 1918, respectively. These devices are indicated in Figs. 1 and 2, and

for a full description of the same reference may be had to the patents just mentioned. The smoke flues 58, one for each boiler, extend over the boiler structure and are mounted on the front and rear walls 45, 46, and 70 the dividing walls 52, as shown in Figs. 1 and 2. The arrangement of the flue over the boiler structure as shown is advantageous in that it permits the gases to rise and escape vertically and eliminates short-circuiting of 75 any of the heating surface.

It is to be understood that the invention is not limited to the specific construction herein illustrated and described but can be embodied in other forms without departure 80 from its spirit as defined by the following claims.

I claim:

1. A steam generator comprising a plurality of similar steam generating sections 85 arranged side by side, each section having two rows of upright water tubes, each row being inclined from the vertical to provide with the inclined tubes of the adjacent section a secondary combustion chamber having a progressively greater volume toward the bottom, and a primary combustion chamber common to all the sections, all said sections being adapted to receive radiant energy from the primary combustion chamber. 90

2. A steam generator comprising a plurality of similar steam-generating sections arranged side by side and having a secondary combustion chamber between each two sections; a primary combustion chamber; 100 and a layer of bricks extending over the entire primary combustion chamber, exposed to the radiant heat of the fuel in said chamber, and providing constricted passages for the gases from the primary combustion 105 chamber to the secondary combustion chambers whereby the gases leaving the primary chamber are thoroughly commingled and brought into close contact with the highly heated brickwork. 110

3. A steam generator comprising a plurality of similar steam-generating sections arranged side by side and provided with a secondary combustion chamber between each two sections; a primary combustion chamber common to all the sections; a series of brick twyers arranged over the entire primary combustion chamber, exposed to the radiant heat of the fuel in said chamber and located in the passages between the said 120 chamber and the secondary chambers whereby gases passing into the secondary chambers are contracted and brought into close contact with the highly heated twyers; and means for supplying preheated air to the 125 twyers for discharge thereby into the currents of gases passing into the secondary chambers.

4. A steam generator comprising a plurality of similar steam-generating sections 130

- arranged side by side but having spaces between them at the bottom to admit radiant heat and furnace gases from below, each section having upright water-tubes arranged in two rows, the tubes being staggered and each tube being bent to extend over the aforesaid spaces for exposure to the said radiant heat and to provide secondary combustion chambers one between each two sections of the generator; a primary combustion chamber below and common to all the sections; and a series of twyer bricks extending over the entire primary combustion chamber at the bottom of the sections and located in staggered formation between the upright water-tubes across the aforesaid spaces between the sections so that the bricks, one between each two tubes, are directly exposed to radiant heat from the primary combustion chamber, and the gases from the latter are contracted and brought into close association with the highly heated bricks in passing between the same into the secondary combustion chambers above.
5. A steam-generator comprising a plurality of similar steam-generating sections of symmetrical form extending from front to rear and arranged side by side; a plurality of vertical drums connected to said sections and at each end thereof, and means for supplying feed-water to each of said drums, said means including a pipe extending from the upper part to the drum within the same and opening adjacent the bottom of the drum whereby the water in the pipe is preheated by the steam and water in the drum.
6. In a steam generator comprising a plurality of similar sections arranged side by side and extending from front to rear, a steam-generating section composed of a horizontal upper drum, a horizontal lower drum of smaller diameter than the upper and located directly below the same, a plurality of upright water tubes connecting the drums, a pair of heat-insulated vertical drums, one at each end of the section, connecting the upper and lower drums, and means for delivering feed-water to each vertical drum, and preheating same within the drum before it is mixed with the water in the drum, whereby a balanced feed and a balanced circulation can be maintained within the section and independently of every other section.
7. In a steam generator comprising a plurality of steam-generating sections arranged side by side and extending from front to rear, a section composed of upper and lower drums one directly below the other, a plu-

rality of upright water-tubes connecting the drums, vertical heat-insulated water-circulating drums connecting the upper and lower drums, at the ends thereof, open-topped sediment pipes extending downwardly in the vertical drums, and feed-water pipes extending downwardly into the sediment pipes and discharging into the same.

8. In a sectional steam generator, a steam-generating section comprising horizontal upper and lower drums and a plurality of upright water-tubes connecting the drums, arranged in laterally spaced rows, the tubes of each row being staggered with respect to the tubes of the other and each tube being bent outwardly at the top, then inwardly and extending in an inward direction to a point near the lower drum and being bent thence outwardly and inwardly into connection with the lower drum, said drums being spaced apart to permit radiant heat to reflect directly upon the tubes, said configuration of the tubes forming inclined tubes adapted to directly receive radiant heat rays at an angle throughout substantially the entire length thereof, said configuration also preventing the entire shading of one tube by another or the shading of one portion of a tube by another portion on the same side of the tube.

9. A sectional steam generator composed of a plurality of steam-generating sections arranged side by side, each comprising a horizontal upper drum, a horizontal lower drum of smaller diameter arranged directly below the upper, and a plurality of upright water-tubes connecting the drums, arranged in two laterally spaced rows, the tubes of one row being staggered with respect to the other, the tubes all curving outwardly from the upper drum into the spaces between adjacent sections and extending thence inwardly to a point near and directly above the lower drum, and curving thence outwardly over said spaces and inwardly into connection with the lower drum, said drums being spaced apart to permit radiant heat to reflect directly upon the tubes, said configuration of the tubes forming inclined tubes adapted to directly receive radiant heat rays at an angle throughout substantially the entire length thereof, said configuration also preventing the entire shading of one tube by another or the shading of one portion of a tube by another portion on the same side of the tube.

In testimony whereof I hereunto affix my signature.

CHARLES A. HORN.
